UNITED STATES PATENT OFFICE.

GEORGE R. HENDERSON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

SECTION FOR BOILERS AND OTHER CONTAINERS.

1,025,697.

Specification of Letters Patent.

Patented May 7, 1912.

Application filed October 21, 1911. Serial No. 655,870.

To all whom it may concern:

Be it known that I, GEORGE R. HENDERSON, a citizen of the United States, residing in Philadelphia, Pennsylvania, have invented certain Improvements in Sections for Boilers and other Containers, of which the following is a specification.

This invention relates to certain improvements in a boiler in which the shell is made of a series of channel sections secured together and to stay plates, although the invention can be applied to any container in which the shell is arranged to resist internal pressures.

15 The main object of the invention is to so construct the channel sections that they will resist any lateral bending strains which would open the joints; the strain being only a shearing strain upon the rivets.

20 A further object of the invention is to so construct the channel sections that a tight joint is provided where the sections are secured to the mud ring.

25 The invention is also designed to equalize the strains and make it easier to calculate the strains than heretofore in this type of boiler using channel sections.

In the accompanying drawing:—Figure 1, is a sectional view of a channel section made in accordance with my invention; Fig. 2, is a detached perspective view of a bent channel section ready to be placed in position to form the shell of a boiler; Fig. 3, is a longitudinal sectional view of the fire box end of a locomotive boiler illustrating my invention; Fig. 4, is an enlarged sectional view on the line 4—4, Fig. 3; and Fig. 5, is an enlarged sectional view on the line 5—5, Fig. 3.

40 Referring in the first instance to Fig. 3, A is the outer shell of the boiler made of a series of channel sections B. The flanges b of these channel sections project outwardly and secured between these sections are the 45 stay plates C. D, D are the U-shaped sections forming the fire box casing. These sections are of the same width as the sections B and their flanges d project inwardly, and the stay plates C are mounted between these 50 flanges. The stay plates are riveted or otherwise secured between the flanges b of the outer channel sections B and between

the flanges d of the fire box sections D. I lay no claim to this particular construction.

Heretofore the channel sections have been 55 made from flat plates bent into shape; the plates being of an even thickness throughout, and when the plates are bent to form the channel sections the corners are rounded and the web is usually slightly arched. I 60 have found that this form of section is objectionable in that the internal pressure tends to open the joints between the stay plates and the flanges of the sections, and there is a tendency to bend the sections at 65 the points near the rivets. Furthermore it is very difficult to calculate the strains on a plate of this particular contour.

The plate of my invention is preferably shaped by rolling; the web b' being thicker 70 at the middle than at the points where it joins the flanges b, b. In fact, the section is thinnest on the line x—x some distance from each flange and the outer wall y of each flange is at right angles with the inner wall z of the web, and the junction of these two walls forms a comparatively sharp edge v, as clearly shown in Fig. 1, so that when the sections are riveted together the flange fits against the stay plate throughout its 75 80 entire width, and the caulking is done at the outer end of the flange between the flange and the stay plate.

The parts are so proportioned that when the section is under ordinary pressure there 85 is no bending action of the section to open the joint between the flange and the stay plate and, if there is any bend under excessive pressure, it takes place some distance from the flange on the line indicated at 90 x—x, but the strain is a shearing strain on the rivets instead of a bending strain. The inner wall z of the channel section is straight and, therefore, the sections fit neatly against the mud ring E to which the 95 sections are secured by rivets, Fig. 5, making a very simple and tight joint. The outer wall w of the web b' may be of any curve desired. The strains on the form as illustrated can be readily calculated, insuring accuracy in construction.

I claim:—

1. A channel section for boiler and other containers subjected to internal pressures,

said section having a web and flanges projecting from one side thereof; the web being thicker at the center than at the edges and the flanges being thicker than the web 5 adjacent thereto.

2. A section for a steam boiler or other container subjected to internal pressures, said section having a web and flanges projecting from one side thereof; said section 10 being curved longitudinally, the web in cross section having its inner surface straight and its outer surface curved, the flanges and the central portion of the web being thicker than the web adjacent the 15 flanges.

3. A section for a boiler or other container subjected to internal pressures, having a web and flanges, said section being curved longitudinally, the inner surface of the web 20 of said section being straight and the outer surface being curved, the outer surface of each flange being at right angles with the straight surface of the web, the web near each end having a section thinner than the 25 body of the web.

4. A boiler having an outer shell composed of a series of channel sections curved longitudinally, the flange of each section being secured to a stay plate, the inner sur-

face of the web of each channel section being straight, the outer surface of the web being convexly curved, and the flanges of the channel sections being thicker than the web adjacent to said flanges.

5. As a new article of manufacture, a 35 rolled channel section for boilers and other containers, having a web, and flanges projecting from the web at one side, the web being thicker at the middle than at the edges and the flanges being thicker than 40 the thinnest portion of the web, the flanged side of the web being curved transversely, the other side being straight, and the outer surfaces of the flanges being straight and at right angles to the straight surface 45 of the web.

6. A channel section for boiler and other containers subjected to internal pressures, said section having a web and flange projection from one side thereof; the web being thicker at the center than at the edges.

In testimony whereof, I have signed my name to this specification, in the presence of two subscribing witnesses.

GEORGE R. HENDERSON.
